UNITED STATES PATENT OFFICE.

DOCK J. PEELER, OF NASHVILLE, TENNESSEE.

PISTON.

Application filed July 8, 1925. Serial No. 42,239.

To all whom it may concern:

Be it known that I, DOCK J. PEELER, a citizen of the United States, residing at Nashville, in the county of Davidson and 5 State of Tennessee, have invented certain new and useful Improvements in Pistons, of which the following is a specification.

This invention relates to pistons for use in connection with internal combustion 10 motors wherein an explosion chamber is arranged in advance of the piston and an oil chamber at the rear thereof in which the connecting rod and crank operate in oil, and the invention has for its object to pro- 15 vide, in a manner as hereinafter set forth, means for setting up a trapping action for the oil, during the operation of the piston, thereby reducing the pumping of the oil to the explosion chamber to a minimum, 20 under such conditions materially increasing the efficiency of the motor.

Further objects of the invention are to provide, in a manner as hereinafter set forth, a piston for the purpose referred to, 25 which is simple in its construction and arrangement, strong, durable, compact, thoroughly efficient in its use, and comparatively inexpensive to manufacture.

With the foregoing and other objects in 30 view, the invention consists of the novel construction, combination and arrangement of parts, as hereinafter more specifically described and illustrated in the accompanying drawings, wherein is shown an embodiment 35 of the invention, but it is to be understood that changes, variations and modifications can be resorted to which come within the scope of the claims hereunto appended.

In the drawings wherein like reference 40 characters denote corresponding parts throughout the several views:—

Figure 1 is a fragmentary view, in sectional elevation, of a motor cylinder and a piston in accordance with this invention.

Figure 2 is a fragmentary view, in longitudinal section, of the piston and its cylinder.

Figure 3 is a perspective view of one form of an expandable combined double acting valve, packing and trap former element.

Figures 4 to 13, both inclusive, are longitudinal sectional views, each illustrating a modified form of piston construction positioned within a cylinder.

In each of the forms shown, the piston body referred to generally by the reference

character 1, is provided with a forwarded terminal part 2 of greater thickness than the remaining rear part 3 of the body portion 1 of the piston. The forward end of the piston is closed by a head 4. The forward thickened part 2 of the body portion 1 is provided with a forward, an intermediate and a rear peripheral groove indicated respectively at 5, 6 and 7, and which are arranged in close proximity to each other, but in spaced relation and with the groove 5 arranged in proximity to the forward face of the body portion 1. The forward and rear side walls of the groove 5 are indicated respectively at 8, 9, and each of which constitutes a valve seat. The forward and rear side walls of the groove 6 are indicated respectively at 10, 11, and each of which constitute a valve seat, and the forward and rear side walls of the groove 7 are indicated at 12, 13 respectively and each of which constitutes a valve seat.

With reference to Figures 1 and 2, there is mounted in the grooves 5, 6 and 7 expandable combined double acting valve, packing and trap former elements 14, 15 and 16 respectively, each in the form of a split annulus. Each of said elements is slightly less in thickness than the width of its respective groove. The element 14, in cross section, has its forward face 17 extending in the same plane throughout and constituting a valve abutting against the seat 8 on the rear stroke of the piston. The rear face of the element 14 has its outer portion 18 inset with respect to its inner portion 19 to provide in connection with the wall 9 of the groove 5 a trap 20. The inner portion 19 of the rear face of the element 14 constitutes a valve, and abuts against the rear wall 9 of the groove 5 on the forward stroke of the piston. By this construction the element 14 provides what may be termed a double acting valve on the reciprocation of the piston for the purpose of trapping the oil to prevent its passage around the forward end of the piston or to reduce the passage of oil in such particular to a minimum, under such conditions preventing or materially reducing oil pumping.

The providing of the inset portion 18 on the rear face of the element 14 forms a shoulder 21, which is disposed parallel to the axis of the piston and the arrangement of the outer portion 18 and inner portion 19 on the rear face of the element 14 is such

that the portions 18 and 19 will extend in parallel planes in cross section.

The element 15, as well as the element 16, has the outer portion of its forward face 5 inset, as at 22. The inner portion 23 of the forward face of the elements 15 or 16 constitutes a valve and coacts with the forward side wall of a groove 6 or 7. The rear face of the element 15, as well as the element 16, 10 has the outer portion 24 thereof inset with respect to the inner portion 25 thereof, and said inner portion 25 constitutes a valve and coacts with the rear side wall of the grooves 6 or 7. In cross section, the portions 22 and 15 23, and 24 and 25 extend in parallel planes. The insetting of the portion 22 and the portion 24 provides a shoulder 26, in cross section, arranged in parallelism with respect to the axis of the piston. The inset portion 22 20 of the element 15, in connection with the forward side wall of the groove 6, provides an oil trap 27. The inset portion 24 of the element 15, in connection with the rear wall 11 of the groove 6, provides a trap 28. The 25 inset portion 22 of the element 16, in connection with the forward wall 12 of the groove 7, provides a trap 29, and the inset portion 24 of the element 16, in connection with the rear side wall 13 of the groove 7, 30 provides a trap 30. The operation of the elements 15 and 16 during the reciprocation of the cylinder is the same as element 14.

With reference to Figure 4, the elements 35 of the set of expansible, combined double acting valve, packing and trap former elements, are indicated at 14', 15' and 16' and operate and are arranged in the same manner as elements 14, 15 and 16. Element 14' is constructed similar to element 14, and elements 15' and 16' are constructed similar to 40 element 14', that is to say, elements 15' and 16' only have their rear faces inset and each of which provides a single trap 17'. Element 14' provides a single trap 18'. The 45 traps 17' and 18' are formed by the rear faces of the elements 14', 15' and 16' only.

With reference to Figure 5, the elements 50 of the set of expansible combined double acting valve, packing and trap former elements are arranged in the same manner as elements 14, 15 and 16 with respect to the grooves in the piston. The elements of said set are indicated at 31, 32 and 33 and are constructed in the same manner as elements 55 14, 15 and 16, but with this exception, that the shoulders formed on said elements, and which are indicated at 34, are curved.

With reference to Figure 6, the elements 60 of the set of expansible combined double acting valve, packing and trap former elements, are indicated at 31', 32' and 33' and are constructed similar to elements 31, 32 and 33 with the exception that the shoulders 34' thereof are inclined.

65 With reference to Figure 7, the elements

of the set of the expansible combined double acting valve, packing and trap former elements are indicated at 35, 36 and 37, and are constructed and arranged similar to elements 14', 15' and 16', with this exception, 70 that the shoulders 38 thereof are curved.

With reference to Figure 8, the elements 75 of the set of expansible combined double acting valve, packing and trap former elements are indicated at 35', 36' and 37', and are constructed and arranged similar to elements 35, 36 and 37, with this exception, that the shoulders 38' thereof are inclined.

With reference to Figure 9, the elements 80 of the set of expansible combined double acting valve, packing and trap former elements are indicated at 39, 40 and 41. The forward face 42 of the element 39, in cross section, extends in the same plane throughout. The outer portion of the rear face of the element 39 extends inwardly at an inclination, as at 43, with respect to the inner portion 44 of said rear face. The portion 43, in connection with the rear side wall of the groove 5, provides a trap 45. The element 40 has the outer part of its forward and its rear face extended inwardly at an inclination, as at 46, 47, thereby forming in connection with the walls of the groove 6, traps 48, 49 respectively. The element 41 is constructed in the same manner as element 40 and provides in connection with the side walls of the groove 7 traps 50, 51. The elements 39, 40 and 41 operate in the same manner as elements 15, 16 and 17. 95

With reference to Figure 10, the elements 100 of the set of expansible combined double acting valve, packing and trap former elements are indicated at 39', 40' and 41' and are arranged and operated in the same manner as elements 39, 40 and 41. The element 39' is constructed similar to the element 39. The elements 40' and 41' are constructed alike and each of which has the outer part of its rear face bevelled inwardly, as at 42'. The elements 39', 40' and 41', in connection with the rear side walls of said grooves, provide traps 43'. 105

With reference to Figure 11, the elements 115 of the set of expansible combined double acting valve, packing and trap former elements are indicated at 52, 53 and 54 and operate and are arranged in the same manner as elements 14, 15 and 16. The element 52 is constructed in the same manner as element 14, and the trap formed thereby is indicated at 55. The forward faces of the elements 53 and 54 are constructed alike and each has the outer portion of its forward face inwardly bevelled, as at 56, to provide a trap 57. The rear faces of the elements 53 and 54 are similar to the rear faces of the elements 15, 16, and provide traps 58 in connection with the rear walls 120 of the grooves 6 and 7. 125

With reference to Figure 12, the elements of the set of expansible combined double acting valve, packing and trap former elements are indicated at 52', 53' and 54' and 5 are similar in construction to the elements 52, 53 and 54, with this exception, that the shoulders 53' thereof are bevelled.

The construction shown in Figure 13 is the same as that shown in Figure 12, with 10 this exception, that the shoulders 59 of the expansible combined double acting valve, packing and trap former elements 60, 61 and 62 are curved in lieu of bevelled, as disclosed in Figure 12.

15 The traps shown in Figure 12 and formed by the elements 52', 53' and 54', in connection with the walls of the grooves are indicated at 56'. The traps formed by the elements 60, 61 and 62 shown in Figure 13, in 20 connection with the walls of the grooves are indicated at 63.

The depth of each of the traps formed by the follower faces of the rings in connection with the rear walls of the grooves, is approximately 25 half the width of the body of the ring. The width of each of the traps, formed by the follower face of the rings, in connection with the rear wall of the grooves, in Figures 1 to 8 and 11 to 13, is less than 30 a quarter of the width of a groove, and this statement also applies to the forward traps disclosed in Figures 1, 2, 5 to 8 and 11. The depth of the forward traps is approximately 35 half the width of the body of the ring.

The diameter and construction of each of the expansible combined double acting valve, packing and trap former elements of a set, as well as the arrangement of the set with 40 respect to the piston body, provides means for trapping the lubricant to prevent oil from being pumped into the piston or combustion chamber of the engine, and it furthermore provides means to increase lubrication due to the fact that the lubricant is 45 trapped in view of the manner in which the set of elements operates during the reciprocation of the piston body, and although the preferred constructions are as described and 50 illustrated, yet changes in the details thereof can be had which will fall within the light of the invention as claimed.

What I claim is:—

1. A group of spaced piston rings for 55 mounting in the grooved periphery of a piston to prevent oil pumping consisting of at least three in number, each of said rings having the outer portion of the follower face thereof inset to provide in connection with 60 the rear side wall of the groove in which it is mounted a trap opening at the periphery of the piston, each of the opposed walls of each trap extending in the same plane throughout and arranged in parallelism 65 throughout, each of said traps of a depth

approximately half the width of the body of a ring and of a width less than a quarter of the width of a piston groove.

2. A piston comprising a body portion provided in proximity to its head with a 70 forward, an intermediate and a rear groove arranged in close relation, the opposed walls of each of said grooves providing a pair of valve seats, and an annular, expansible, combined, double-acting valve, packing and trap 75 former element mounted in each of said grooves and each having its forward face intermittently and alternately engaging the forward and rear walls of its respective groove on the reciprocation of the piston, 80 said forward element having its forward face, in cross section, extending in the same plane throughout, each of said elements in cross section having the outer portion of its follower face positioned forwardly of and in a plane parallel to the plane of the inner portion of such follower face and forming in connection with the rear wall of a groove 85 a trap of a depth approximately equal to half the width of the body of each element, 90 and each of said elements mounted in said intermediate and rear grooves, in cross section, having the outer portion of its forward face formed to provide in connection with the forward wall of its respective 95 groove a trap of a depth approximately half the width of the body of an element.

3. A piston comprising a body portion provided in proximity to its head with a 100 forward, an intermediate and a rear groove arranged in close relation, the opposed walls of each of said grooves providing a pair of valve seats, and an annular, expansible, combined, double-acting valve, packing and trap 105 former element mounted in each of said grooves and each having its forward face intermittently and alternately engaging the forward and rear walls of its respective groove on the reciprocation of the piston, 110 said forward element having its forward face, in cross section, extending in the same plane throughout, each of said elements in cross section having the outer portion of its follower face positioned forwardly of and in a plane parallel to the plane of the inner portion of such follower face and forming in connection with the rear wall 115 of a groove a trap of a depth approximately equal to half the width of the body of each element, and each of said elements mounted 120 in said intermediate and rear grooves, in cross section, having the outer portion of its forward face formed to provide in connection with the forward wall of its respective 125 groove a trap of a depth approximately half the width of the body of an element, the said rear traps of a width less than a quarter of the width of the piston groove.

4. A piston comprising a body portion provided in proximity to its head with a 130

forward, an intermediate and a rear groove arranged in close relation, the opposed walls of each of said grooves providing a pair of valve seats, an annular, expansible, combined, double-acting valve, packing and trap former element mounted in each of said grooves and each having its forward face intermittently and alternately engaging the forward and rear walls of its respective 5 groove on the reciprocation of the piston, said forward element having its forward face, in cross section extending in the same plane throughout, each of said elements in cross section having the outer portion of its 10 follower face positioned forwardly of and in a plane parallel to the plane of the inner portion of such follower face and forming in connection with the rear wall of a groove a trap of a depth approximately equal to 15 half the width of the body of each element, each of said elements mounted in said intermediate and rear grooves, in cross section, having the outer portion of its forward face formed to provide in connection with the 20 forward wall of its respective groove a trap of a depth approximately half the width of the body of an element, and each of said elements mounted in said intermediate and rear grooves having the outer portion of its 25 forward face inclining rearwardly with respect to the forward side wall of the groove 30 forward face inclining rearwardly with respect to the forward side wall of the groove

in which the element is mounted, thereby providing in connection with said wall a trap gradually increasing in width outwardly and of a depth approximately equal to 35 half the width of the body of the element.

5. A group of spaced piston rings for mounting in the grooved periphery of a piston to prevent oil pumping consisting of at least three in number arranged one in 40 advance of the other, each of said rings having the outer portion of the follower face thereof formed to provide in connection with the rear wall of the groove in which the ring is mounted a trap, each of 45 said rings, with the exception of the forward ring, having the outer portion of its forward face inclining rearwardly with respect to the forward side wall of the groove in which the ring is mounted, thereby providing in connection with such wall a trap gradually increasing in width outwardly and of a depth approximately half the width of the ring, the said rings other than the forward one, having its outer outer edge of 50 less width than its inner edge and further having its forward and follower face terminating in the ends of and spaced from each other by said outer edge.

In testimony whereof, I affix my signature hereto. 60

DOCK J. PEELER.
